UNITED STATES PATENT OFFICE.

COLUMBUS M. LANE, OF CLARENDON, TEXAS.

VALVE FOR WATER SYSTEMS.

Application filed May 27, 1924. Serial No. 716,262.

To all whom it may concern:

Be it known that COLUMBUS M. LANE, a citizen of the United States of America, residing at Clarendon, in the county of 5 Donley and State of Texas, has invented new and useful Improvements in Valves for Water Systems, of which the following is a specification.

The present invention has for its purpose to provide a valve for a water system 10 wherein the water pressure may be taken care of under normal conditions so that, should there be an increased demand on the supply, water from a reserve source may 15 be used to supply this increased demand.

Another purpose is to provide a valve to be used in a water system, the valve being open under normal conditions but adapted to be closed automatically by the water furnished under increased pressure to extinguish fires, so that, during such use of 20 the water under increased pressure, no water will pass through the normal system.

Still another purpose is the provision of 25 a valve carried by a guide rod and cooperating with a seat in one end of a relatively small piping and being held normally open through the medium of a spring, in conjunction with a cupped member on a rod at 30 the other end of a relatively small pipe for the purpose of receiving the water and overcoming the opposing force of the spring; so as to close the valve in case of increased pressure.

35 A further purpose is to provide in a valve a construction for multiplying the effective force of the stream passing through the valve body and also an arrangement of a rod or stem with the elimination of packing around the stem which would otherwise create friction and prevent free movement of the rod.

A still further purpose is to provide a 45 valve including a valve head with its area of clearance around the head equal to the cross sectional area of the intermediate portion of the valve body, there being a valve seat at one end of the valve body with which the valve head engages, there also being no parts to cause undue friction.

Moreover, the valve includes a cupped member which may be fastened to the valve rod or stem operable in the path of the water at the other end, there being clearance around the valve head and no friction 55 to retard its movements.

Furthermore, the invention aims to provide means to adjust the tension of a spring or other resilient means which holds the valve open during the normal flow of water 60 through the valve body, the casing or valve body including plugs at its ends which can be removed, and by removing certain other plugs and loosening the valve head proper with respect to its stem, the whole 65 working parts of the valve proper can be removed without molesting the valve body.

It is to be understood that the particulars herein given are in no way limitative and that while still keeping within the scope of 70 the invention, any desired modifications of detail and desired proportions may be made in the apparatus according to the circumstances.

The invention comprises further features 75 and combinations of parts to be hereinafter set forth, shown in the drawings and claimed.

In the drawings:

Figure 1 is a view in elevation of a portion 80 of a water system piping showing applied to a valve constructed in accordance with the invention.

Figure 2 is a sectional view through the 85 valve casing more clearly showing the construction of the valve and its mounting, with the valve open.

Figure 3 is a view similar to Figure 2, with the valve closed.

Referring to the drawings, 1 designates 90 a piping for a substantial flow of water comprising an inlet pipe 2^a to the valve body and an outlet pipe 2^b from the valve body, there being a pipe 3^a connecting the inlet and outlet pipes and adapted to extend to any suitable location to provide for the consumption of the water. A check valve 3^b is located in the connecting pipe 95 3^a to insure the passage of water through the valve body rather than through the connecting pipe to the location of the water consumption.

The improved valve construction includes means 100 providing for holding the valve proper open during the normal flow of water through the valve casing in conjunction with means on the valve rod with which an increased supply of water under greater pressure impinges, relying upon the 105 kinetic energy of the stream of water to close the valve. In some systems where it is the aim to employ this improved valve, 110

provision may be made for reserve source, so that should there be a demand for an increased supply of water, the reserve source may be called upon to supply this demand. This valve 2 comprises a casing consisting of T's 16 and 17 which are axially arranged and are connected to a reduced pipe section 18 and couplings 19 and 20.

The remote ends of the T's 16 and 17 are closed by means of plugs 21 and 22 through which the short sections of pipes 23 and 24 are arranged. The remote ends of the pipe sections 23 and 24 are closed by nuts or caps 25 and 26. The T's 16 and 17 have laterally positioned flanged openings 16^a and 16^b closed by the plugs 17^a and 17^b. These plugs 17^a and 17^b may be removed to permit an instrument to be inserted for loosening the valve proper and a member on the stem of the valve. When either the valve proper or said member is loosened, the stem and its attendant parts may be removed by first removing one or both of the plugs 21 and 22.

The pipe sections 23 and 24 are threaded through the plugs 21 and 22, there being lock nuts 23^a and 24^a to hold the short pipe sections in position, adjusted accordingly. The pipe section 24 may be adjusted to increase the tension of the spring which cooperates with the stem to hold the valve proper open. Obviously, by removing the plugs 17^a and 17^b, an instrument may be inserted for adjusting the position of the valve proper and the member on the stem, said member, when adjusted, also governing the tension of the spring previously mentioned.

Mounted for movement and guided in the short pipe sections 23 and 24 is a valve rod 29, a suitable web or spider 27 with a guide 28 being provided for the medial portion of the valve rod. This web or spider constitutes an integral part of the reduced pipe section 18. Secured upon the valve rod 29 by means of the set-screw 32^a is a valve 32 which is designed to cooperate with a valve seat 33 disposed adjacent the coupling 19. The valve seat 33 constitutes one end of the reduced pipe section 18 which is threaded through the couplings 19 and 20. Also secured to the valve rod 29 by means of a set-screw 34^a is a cupped member 34 which, as previously stated, can be loosened or adjusted by removing the plug 17^b and inserting a tool to accomplish loosening the member. A suitable washer 29^a is mounted upon the valve rod 29 adjacent the inner end of the short pipe section 24 and interposed between the washer 29^a (which bears against the inner end of the pipe section 24) and the cupped member 34 is a coil expansion spring 37. As previously mentioned, the tension of this spring can be regulated by adjusting the cupped member 34 or by

adjusting the pipe section 24. The spring cooperates with the cupped member and holds the valve 32 normally disengaged from its seat 33, so long as there is a normal flow of water through the pipe section 18. 70

The valve has an adjacent gasket and when the pressure of water in the pipe 2^a is greater, the kinetic energy of the stream of water behind and impinging with the cupped member 34 imparts movement to 75 the cupped member and the rod and its valve proper, closing the valve and causing the gasket to cooperate with the seat to insure cutting off the water. The valve rod 29 has a collar 29^b adjustably secured by means of a set-bolt 29^c and which collar 29^b cooperates with the spider 27 to limit the valve in its open position.

When an amount of water under normal conditions is passing through the valve 85 body, kinetic energy of the water, as it leaves the end of the reduced pipe section 18, is insufficient to acutate the cupped member, the rod and its valve proper. The action of the water against the valve and the 90 cupped member under normal conditions is not great enough to move them to any marked degree against the force of the spring. Thus, the water may pass through the piping. However, it will be noted that 95 the pipe section 18 is reduced with respect to the pipe 2^a. Therefore, when the pressure of water in the pipe 2^a is greater and since the clearance around the valve 32 and the cupped member 34 is substantially equal 100 to the area of the pipe section 18, the kinetic energy of the stream of water, as it leaves the pipe section 18, increases and impinges on the cupped member, thereby actuating the valves 32 to a closed position. 105

When the supply of water is greater, such as is often necessary for obvious reasons, the action of the water on the valve and cupped member increases and obviously overcomes the tension of the spring 37, 110 thereby causing the valve 32 to close against its seat. Prior to the greater supply of water in the pipe 2^a, there is a normal pressure of water in the pipe section 18. The water under abnormal conditions passes rapidly out through the T 17 and with substantial energy. The water as it leaves the section 18 operates upon the cupped member 34 with sufficient effective force in order to overcome the opposing force of the 115 spring, thus actuating the valve head to engage the valve seat, a water-tight joint being assured.

This method of operation throws all the 125 pressure of the excess water supply from its source and into a hose which may connect to the piping in any manner (not shown). However, should the valve 32 be allowed to remain open, the water supply and pressure will be divided between the source of 130

supply and the source of consumption. As soon as the kinetic energy of the water, as it leaves the reduced pipe section 18, reduces, the spring 37 forces the valve open, restoring it to its normal position. The valve is controlled entirely by the effective force of the water.

The invention having been set forth, what is claimed is:

10 1. A valve for a water system comprising a casting with a valve seat therein, a valve rod loosely guided in the casing, thereby doing away with packing and reducing friction to a minimum, a valve head on the rod and cooperating with the seat, and removable guides at the remote ends of the casing and in which said rod is loosely mounted, said removable guides comprising detachable plugs, the removal of which and the loosening of the valve head permits the working parts of the valve to be removed without molesting the valve body.

20 2. A valve for a water system comprising a casing with a valve seat therein, a valve rod loosely guided in the casing, thereby doing away with packing and reducing friction to a minimum, a valve head on the rod and cooperating with the seat, removable guides at the remote ends of the casing and in which said rod is loosely mounted, said removable guides comprising detachable plugs, the removal of which and the loosening of the valve head permits the working parts of the valve to be removed without molesting the valve body, expansion means on the valve rod for holding the valve open under a normal flow of water, and means for regulating the tension of the expansion means.

40 3. A valve for a water system comprising a casing having inlet and outlet openings at its remote ends and an intermediate valve seat, a valve rod mounted for reciprocating movement in guides of the casing and including a valve cooperating with the seat, means for cooperating with the rod for holding the valve open during a normal flow of water through the casing, and means on the rod a remote distance from the valve and with which an increased supply of water flowing past the valve with greater pressure impinges, whereby the kinetic energy of the water closes the valve.

55 4. A valve for a water system comprising a casing with an intermediate reduced portion with a valve seat at one end, a valve rod mounted for reciprocating movement through the intermediate reduced portion of the casing with a valve to cooperate with a seat, means cooperating with the valve rod for holding the valve normally open during a normal flow of water, and a member carried by the valve rod a remote distance from the valve and with which member and the valve the water flowing past

the valve impinges during an increased supply with greater pressure, whereby the kinetic energy of the water closes the valve against the seat, the construction and arrangement of the valve and the member with respect to the remote ends of the reduced portion of the casing being such as to provide clearance equal to the area of said reduced portion.

5. A valve for a water system including a casing with an intermediate guide portion having a valve seat at one end and a valve rod operable through the intermediate guide portion and provided with a valve to cooperate with the seat which is at one end of the guide portion, said valve rod having a member adjacent the other end of the guide portion with spring means cooperating with the member to hold the valve normally open, the construction and arrangement of the valve and the member with relation to the ends of the intermediate guide portion being such as to cause a substantial clearance equal to the area of the intermediate guide portion, whereby the increasing of the kinetic energy of the water as it discharges from the intermediate guide portion may impinge on said member and close the valve.

6. A valve for a water system comprising a casing having inlet and outlet openings at its remote ends, and an intermediate valve seat, a valve rod mounted for reciprocating movement in guides of the casing and including a valve cooperating with the seat, means cooperating with the rod for holding the valve open during a normal flow of water through the casing, means on the rod a remote distance from the valve and with which an increased supply of water flowing past the valve with greater pressure impinges, whereby the kinetic energy of the water closes the valve, and abutment means intermediate the ends of the casing for limiting the valve in its open position.

7. A valve for a water system comprising a casing with an intermediate reduced portion with a valve seat at one end, a valve rod mounted for reciprocating movement through the intermediate reduced portion of the casing with a valve to cooperate with the seat, means cooperating with the valve rod for holding the valve normally open during a normal flow of water, a member carried by the valve rod a remote distance from the valve and with which the valve head the water flowing past the valve impinges during an increased supply of water with greater pressure whereby the kinetic energy of the water closes the valve against its seat, the construction and arrangement of the valve and the member with respect to the remote ends of the reduced portion of the casing being such as to provide clearance equal to the area of said reduced portion, and abutment means in the intermediate re-

duced portion of the casing for cooperating with the rod for limiting the valve in its open position.

8. A valve for a water system including a casing with an intermediate guide portion having a valve seat in one end, a valve rod operable through the intermediate guide portion and provided with a valve to cooperate with the seat which is at one end 5 of the guide portion, said valve rod having a member a remote distance from the valve and adjacent the other end of the guide portion with spring means cooperating with the member to hold the valve normally open, 10 the construction and arrangement of the valve and the member with relation to the

ends of the intermediate guide portion being such as to cause substantial clearance equal to the area of said intermediate guide portion, whereby the increasing of the 20 kinetic energy of the water flowing past the valve and as it discharges from the intermediate guide portion may impinge on said member and close the valve, the intermediate guide portion of the casing having 25 a spider in which the rod is guided, and adjustable means on the rod for cooperating with the spider for limiting the valve in its open position.

In testimony whereof he affixes his signature. 30

COLUMBUS M. LANE.
